ABSTRACT OF THE DISCLOSURE

Apparatus for receiving and stacking a series of workpieces discharged from a conveyor belt, sewing machine or the like, featuring a horizontal receiving surface with means for periodically changing the position of the receiving surface with respect to workpieces delivered thereto, so as to make an orderly stack of workpieces on the receiving surface.

This invention relates to apparatus for receiving a series of workpieces discharged from a conveyor belt, sewing machine, or other apparatus, and stacking the same in orderly arrangement on a receiver. In particular, this invention relates to apparatus adapted to receive a succession of cloth workpieces, or workpieces of similar limp, flexible material.

Many devices have been proposed for the purpose of receiving and stacking workpieces discharged from an apparatus performing one operation or another on such workpieces. For example, many devices have been proposed for stacking cardboard carton blanks discharged from the cutting machine, for receiving and stacking printed matter as it emerges from the printing machine, and for similar purposes.

In the handling of fabric workpieces, however, the problem is somewhat different because of the nature of the fabric itself. Thus, machines of the type employed in the manufacture of cardboard carton blanks generally depend for their proper functioning on the stiffness of the cardboard material. Similarly, machines designed to handle paper workpieces such as printed matter also usually depend on the relative stiffness of the paper which, although much less than that of cardboard, is nevertheless appreciable in an edgewise direction. Such machines cannot be successfully employed in connection with a comparatively limp material such as cloth.

In my Patent No. 3,113,771, issued Dec. 10, 1963, entitled "Automatic Pickup for Stacking Material," there is described and claimed an apparatus comprising a reciprocating receiving platform adapted to receive workpieces discharged from a conveyor belt or the like, and form of such workpieces a uniform stack, with the successive workpieces laid flat one atop the other.

The apparatus described and claimed in my said patent is highly effective in stacking workpieces of appreciable width, such as jacket panels, sleeve blanks, skirt blanks, and the like, for subsequent assembly into finished garments. Where the workpieces being received and stacked are small, and particularly where they are long and narrow, such, for example, as belts, collars, skirt bands or the like, there is a tendency for the stack of workpieces to topple over sideways unless pains are taken to keep it from growing too high. One way of overcoming this tendency, also taught in my said patent, is to provide the receiving table with adjustable guide rails which can be moved inwardly toward the center of the table, so as to support the stack on either side, and thus prevent it from toppling over. Although this arrangement is quite effective, it is sometimes desirable that the stacks be self-supporting, rather than being provided with means for supporting them externally.

2

An object of the present invention, therefore, is to provide an improved apparatus for receiving and stacking a series of pieces of cloth or similar material.

Another object is to provide an apparatus for receiving and stacking such materials, which is particularly adapted to the receiving and stacking of small or long and narrow workpieces.

Still another object is to provide apparatus of the type described, which is capable of forming self-supporting stacks from small, or long and narrow workpieces.

A feature of the present invention is the use of a pivotally-mounted receiving surface which is capable of at least some degree of rotation in a horizontal plane.

Another feature of the present invention lies in the use of means for synchronizing the horizontal rotational movement of said receiving surface with the discharge of individual workpieces onto said surface.

Another feature is the combination of a horizontally-rotatable receiving surface with a horizontally-reciprocating undercarriage.

Yet another feature of the invention is the employment of means for correlating the horizontal rotational movement of said receiving surface with horizontal reciprocating movement of said undercarriage in the manner hereinafter to be more fully described.

Other objects, features and advantages of the present invention will become apparent from the following more complete description and claims.

The invention consists in the form, arrangement and selection of parts as more fully described hereinafter, and with reference to the drawings, in which parts appearing in more than one drawing have been given the same reference numeral throughout.

In one particularly desirable embodiment, this invention contemplates an apparatus for receiving and stacking a succession of workpieces, said apparatus comprising in combination a generally horizontal receiving surface, means for periodically altering the position of said receiving surface with respect to workpieces delivered thereto and thereby altering the position on said receiving surface in which said workpieces are delivered, and means for disabling said means for altering the position of said receiving surface when a workpiece is in the process of being deposited on said surface.

Referring now to the figures:

FIGURE 1 is a side elevation of a device according to a preferred embodiment of the invention, namely a combined cross-stacker and square-stacker.

FIGURE 2 is a plan view of the underside of the device of FIGURE 1.

FIGURE 3 is a perspective view showing the apparatus of this invention mounted on a reciprocating pickup carriage and set up to receive and stack workpieces discharged from a conveyor belt.

FIGURE 4 is a top view of a crank assembly useful in another embodiment of the invention.

FIGURE 5 is a front elevation of the crank assembly shown in FIGURE 4.

FIGURE 6 is a somewhat diagrammatic top view of an apparatus according to the invention, using the crank assembly of FIGURES 4 and 5.

FIGURE 7 is a top view similar to FIGURE 6, showing the apparatus of FIGURE 6 at a different stage of operation.

FIGURE 8 is a somewhat diagrammatic top view, similar to FIGURE 6, showing another embodiment of apparatus according to the invention, using a crank assembly of the type shown in FIGURES 4 and 5.

FIGURE 9 is a top view similar to FIGURE 8, showing the apparatus of FIGURE 8 at a different stage of operation.

Referring more particularly to FIGURE 1, the receiving surface is a flat surface 10 of plywood, sheet metal, or any appropriate material, preferably of lightweight construction. On the underside of receiving surface 10 is a square boss 12, designed to fit into a mating recess 14 in collar 16. Collar 16 projects through a suitable aperture in a supporting surface 18, in the form of a table or the like. For purposes of clarity, the receiving surface 10 is shown as being spaced slightly above the supporting surface 18. In the practical construction of the machine, the receiving surface 10 may rest directly on supporting surface 18, preferably with a thin layer of grease or other lubricant between them, or they may be separated as shown, with ball bearings or the like (not shown) in the space between them. In another variation, the weight of the receiving surface and its load may be supported entirely through boss 12 which, in this case, rests on a floor or shoulder (not shown) in collar 16. When the weight is supported in this way, supporting surface 18 may be dispensed with altogether, if desired.

Collar 16 is connected to operating lever 20. The other end of lever 20 is pivotally connected at pivot 22 to push rod 24. Push rod 24, in turn, is pivotally connected at its other end, by way of pivot 26, to one end of rotating rod 28.

Rotating rod 28 is driven in any suitable controllable manner, as by shaft 30 driven by motor 32.

As the apparatus has so far been described, it will be apparent that as motor 32, operating through shaft 30, rotates rotating rod 28, it imparts a reciprocating motion to push rod 24, which in turn causes operating rod 20 to alternate between the positions shown in solid and dotted outline, respectively, in FIGURE 2. The operating lever causes a corresponding angular change in the position of collar 16, recess 14, boss 12, and receiving surface 10.

Surrounding shaft 30, and mounted to rotate freely thereon, is switch disc 34. Switch disc 34 is in the nature of a generally circular cam. The purpose of switch disc 34 and its associated components is to provide a cycling mechanism to control the movements of receiving surface 10, and in particular to ensure that the position of the receiver will be changed only during periods when no workpiece is being deposited thereon. Protruding upwardly from switch disc 34 is a boss 36 projecting into the path of rotating rod 28. As rotating rod 28 rotates, it pushes boss 36 before it, thus rotating switch disc 24, until the disc reaches approximately the position shown in the drawings. At this point one of two identical cam lobes 38, extending radially outward of the generally circular profile of the switch disc, actuates cam follower 40, thereby opening normally-closed switch 42.

Switch 42, by means of suitable electrical connections (not shown), is connected in series with the current supply to motor 32. The result of the arrangement, therefore, is to interrupt the motion of rotating rod 28, push rod 24, and ultimately the angular motion of receiving surface 10, whenever switch disc 34 comes around to the position shown (or the equivalent position 180° away).

This situation persists, and the parts remain stationary relative to one another, until solenoid 44 comes into play. Solenoid 44 is preferably one of the type wherein the core is retracted against a spring bias when the magnetic coil is energized, and is "fired" or partially ejected from the core by the action of the spring, for example spring 46, when the coil is deenergized. Solenoid 44 is connected by suitable electrical connection (not shown) to a sensing device (also not shown in this view) adapted to signal the presence or absence of a workpiece approaching the receiving surface. Such arrangements are known to the art, having been taught, for example, in my U.S. Patent No. 3,113,771, issued Dec. 10, 1963, wherein the sensing device is a photoelectric element associated with a light source in such a position that the light directed from the light source to the photoelectric element is

interrupted by a workpiece as it passes between them on the way to the receiving surface. Thus, in the present apparatus, when a workpiece is approaching the receiver, the light beam for example from lamp 98 to photocell 100 (FIG. 3) is interrupted and current to the solenoid coil is interrupted, whereupon the solenoid "fires."

Associated with solenoid 44 is a rod 48, connected at one end to the solenoid core and at the other to spring 46. A lug 50 projects laterally outward from rod 48, in position such that when the solenoid fires, lug 50 strikes the shoulder of adjacent cam lobe 38, causing a slight additional rotation of switch disc 34, sufficient to move the other cam lobe 38 out from under cam follower 40 and close switch 42. This reactivates the power supply to motor 32, and the cycle repeats.

Suitable precautions should be taken to prevent lug 50 and the second cam lobe 38 from jamming as the cam lobe comes around to the indicated position, while lug 50 is still in the position indicated by dotted lines. This may be accomplished in a variety of ways, for example by providing a solenoid mount flexible enough to allow the lug to be temporarily pushed out of the way by the cam lobe, or by pivoting the lug to the solenoid shaft, so as to allow it to be swung downwardly against a suitable spring bias or the like, by the cam lobe as it passes. These and various other arrangements will be obvious to those skilled in the art.

As will be apparent from the foregoing description, the action of the apparatus as so far described is as follows: Starting from a position of rest as illustrated in FIGURES 1 and 2, when a workpiece begins approaching the receiving surface, it activates the sensing means, and solenoid 44 is cocked in response to the sensing means, against the bias of spring 46. All the other parts remain stationary relative to one another, in the positions shown.

As the trailing edge of the workpiece passes the sensing means, the sensing means so signals by interrupting the current to the coil of solenoid 44, so that the solenoid "fires" in response to the stored energy in spring 46, causing lug 50 to move to the position shown in dotted outline in FIGURE 2. This, in turn, drops cam follower 40 off the shoulder of the cam, closing switch 42 and re-establishing the current supply to motor 32. The motor rotates the rotating rod 28 through 180°, at which time push rod 24 and operating lever 20 are in the respective positions shown in dashed lines (FIGURE 2), and switch 42 is again opened by the other cam lobe 38. As the leading end of the next workpiece passes the sensing means, solenoid 44 is again cocked, and as the trailing edge passes, solenoid 44 is again fired, initiating another 180° movement of the rotating rod, which returns the apparatus to the condition originally illustrated.

The result of the actions just described is that, as workpieces are deposited on the receiving surface, the latter alternates between two angular positions. This in turn, results in the formation of an X-shaped stack, when the workpieces are long, narrow ones, instead of the straight-sided, narrow, unstable stack that would be produced without such angular alternation.

SQUARE STACKING

In some instances, for example where the workpieces being processed are not only narrow relative to their length, but also relatively short, it is desirable to form a square stack, wherein the stack is formed by a succession of workpieces alternately laid down so as to form the four sides of a square. The device of this invention, as illustrated in FIGURES 1 and 2, also provides for stacking workpieces in this manner, if so desired.

According to this aspect of the invention, push-rod 24 is pivotally connected, as at 22, to a pair of operating rods 52, 54, which in turn are pivotally connected as at 56, 58, respectively to operating levers 60, 62. Operating levers 60 and 62 are integral extensions, respectively, of

collars 64 and 66. Collars 64 and 66 surround a hollow shaft 68, which has an internal recess 70 of square or other non-circular cross-section. Collars 64 and 66 are mounted for free rotation in either direction around hollow shaft 68.

Integrally attached to shaft 68 is a notched disc 72, having four indentations, or notches 74.

Each of operating levers 60 and 62 has attached thereto a pawl, 76 and 78, respectively, positioned to be received in notches 74.

The operation of the square stacker is very similar to that previously described for cross-stacking. The receiving surface 10 is lifted up so as to remove boss 12 from recess 14 in collar 16, and placed over hollow shaft 68, so that boss 12 fits into recess 70. Starting from the position of rest as illustrated in FIGURE 1 and in solid lines in FIGURE 2, the various parts remain in their relative positions until the sensing device signals the approach of a workpiece, as previously described in connection with the cross-stacking operation. When the sensing device signals the approach of a workpiece (i.e., when the leading edge of the workpiece interrupts the light to the photoelectric element, for example), solenoid 44 is energized and is cocked against the bias of spring 46. As the trailing edge of the same workpiece clears the sensing device, the coil of the solenoid is de-energized and the solenoid fires, advancing switch disc 34 and closing switch 42, thus starting the motor 32. Motor 32 runs long enough to rotate rotating rod 28 through 180°, and then is stopped by the action of one of cam lobes 38 which opens normally-closed switch 42, as previously described. During this travel, push rod 24 and operating rods 52 and 54 have advanced to the positions shown in dashed lines in FIGURE 2. In the process, pawl 76, on operating lever 60, has advanced notched disc 72 through 90°. Meanwhile, pawl 78, on operating lever 62, has moved to the position shown in dashed lines (FIGURE 2) out of its original notch 74 and into the next notch 74. The parts then maintain their relative positions until solenoid 44 is cocked by the sensing device in response to the leading edge of the next workpiece, and fired in response to the passage of the trailing edge of the same workpiece. When this happens, motor 32 is again energized, and moves rotating rod 28 through 180°. This, in the manner already described, moves push rod 24, operating rods 52 and 54, and operating levers 60 and 62 back to the positions shown in solid lines in FIGURE 2. As they so move, pawl 78 on operating lever 62, rotates notched disc 72 another 90° in the same direction as before (counter-clockwise, as seen from below in FIGURE 2). Meanwhile, pawl 76 lifts out of the notch in which it has been engaged, and moves in the opposite direction (clockwise, as seen in FIGURE 2) into the next succeeding notch 74. Thus, each 180° rotation of the rotating rod 28 produces a 90° rotation in notched disc 72, and consequently in shaft 68 and recess 70, and hence in the position of receiving surface 10. The result is that receiving surface 10 advances by an angular increment of 90° between each workpiece and its successor, resulting in a stack of workpieces having the form of a hollow square.

In order to achieve the results just described, the center of recess 14, for cross-stacking, should be lined up with the center line of the discharge of workpieces onto receiving surface 10, or at least approximately so. The center of recess 70, on the other hand, should be located off the center line of the discharge by an amount approximately equal to one-half the width of the square stack to be produced.

The apparatus of this invention is designed to be used in conjunction with an automatic pickup of the type described and claimed in my aforesaid U.S. Patent No. 3,113,771, as illustrated generally in FIGURE 3, or in conjunction with a similar pickup apparatus. The automatic pickup is designed to receive workpieces being discharged longitudinally off a conveyor belt or the like, 75

in such a way that the workpiece are laid out flat on the receiver, rather than being piled up in a random heap over a single stationary point on the receiver. The apparatus of the present invention is readily added to or built into such a receiver, and provides means for handling long and narrow (or short and narrow) workpieces in a more efficient manner than is possible using only the automatic pickup as disclosed in my aforesaid patent.

As shown in FIGURE 3, supporting surface 18 is mounted above a reciprocating carriage indicated generally by the numeral 80. This carriage is arranged to travel back and forth under the discharge point of the belt in the general direction of belt travel, and is preferably controlled as to speed in such manner that, during those portions of the cycle when a workpiece is being deposited on the receiver, the linear speed of the receiver is substantially equal to the linear speed of the workpiece being discharged onto it. This may be accomplished in the manner disclosed in my aforesaid patent, or in any other convenient manner.

As the carriage reciprocates in the direction of belt travel and at the speed thereof (thus depositing each workpiece in flat disposition on the receiver), the receiving surface 10, in the manner already described, rotates horizontally in angular increments, so that each successive workpiece is deposited at an angle to the one preceding it, thus forming a cross-stack or a square stack, as the case may be.

In some cases, it may be desired to have the receiving surface change its horizontal angular position not after each workpiece is deposited, but rather after the deposition of some predetermined number of workpieces in excess of one. For example, it may be desired to deposit lapel pieces in the form of a cross-stack of pairs of matching pieces—i.e. two matching pieces laid one way, followed by two the other way. This is readily accomplished by interposing a conventional counting switch (not shown) in the circuit in series with the leads to the coil of solenoid 44, so that the solenoid is fired only after two, three, or any predetermined number of pulses from the photocell.

Obviously, if only square stacking is desired, the machine may be constructed more cheaply by omitting collar 16, operating lever 20, and associated parts. By the same token, if only cross-stacking is desired, operating rods 52 and 54, operating levers 60 and 62, collars 64 and 66, hollow shaft 68, and associated parts may be omitted. Also, if desired, separate motors may be provided for the cross-stacking and square-stacking operations, thus eliminating some of the linkages required when using the same motor for both operations. On the other hand, by using suitable clutches or other forms of power takeoff, a single motor can be used not only for changing the position of the receiving surface for square stacking and cross-stacking, but also as the main drive motor for carriage 80, as will be apparent to those skilled in the art. In the preferred form of the invention, however, all the illustrated and described parts are included. This preferred form of machine is much more flexible and versatile, as it may be converted from a square stacker to a cross-stacker, or vice-versa, merely by lifting boss 12 out of one recess and dropping it into another.

In some operations, it is desirable to provide for translational, rather than a rotational displacement of the receiving surface between the deposition thereon of successive workpieces. Examples of this type of operation include those operations in which there is provided a right-hand and a corresponding left-hand piece for each garment—for example lapel fronts and the like. In such cases, it is desirable to arrange the right-hand pieces, in one stack and the left-hand pieces in a separate stack alongside the first stack, but not overlapping or intermeshing with the first stack, as in the operations described above. This type of stacking may be accomplished according to the invention by using the embodiments of the invention illustrated in FIGURES 4-9.

FIGURES 4 and 5 illustrate a crank assembly useful in converting the rotational or angular motions produced as described above, into translational motions. The crank assembly comprises a block 81 having a square cross-section in the horizontal plane, adapted to be received in recess 14 or recess 70 (FIG. 2). A crank arm 82 passes through a suitable channel provided in the upper portion of block 81, and is adapted to be locked in any desired position by set screw 84, thus providing for an adjustment of the effective length of crank arm 82. This adjustable length feature is not essential, but is desirable in that it provides a convenient means of adjusting the extent of translational motion and consequently, the distance between the two stacks.

At the end of crank arm 82 is a boss or the like 86, 15 constituting means for engaging the receiving surface in a manner dependent on the operation to be performed, as described below.

FIGURE 6 shows a plan view of supporting surface 18, equipped with means for translating receiving surface 10^a 20 from side to side, to form two parallel stacks of workpieces.

Supporting surface 18 is provided with means for causing it to reciprocate in the general direction of delivery of the workpieces, as indicated by the double-headed arrow. Such means (not shown), as noted above, may take the 25 form of a reciprocating carriage such as that set forth in my aforesaid patent, or any equivalent means.

Block 81 of the crank assembly is dropped into recess 14 of collar 16 (not visible in this view), and receiving surface 10^a differs from receiving surface 10 (FIGS. 1 and 3) in two respects: it is provided with means in the form of depending flanges 88 for preventing rotational motion of receiving surface 10^a with respect to supporting surface 18, and with means such as depending flanges 90 defining a channel on the underside of receiving surface 10^a, adapted to receive boss 86 on crank arm 82. Suitable support members such as casters or the like (not shown) may be interposed between supporting surface 18 and the underside of receiving surface 10^a, as will be obvious to those skilled in the art, these being omitted from the drawings in the interest of clarity.

As collar 16 alternates between two positions, as described above with reference to the cross-stacking operation, it causes the crank assembly to move correspondingly, from the position shown in FIGURE 6 to that shown in FIGURE 7 and back again, as indicated by the curved arrows. As it does so boss 86, bearing against the depending flanges 90, causes the receiving surface 10^a to move from side to side, between the positions shown respectively in FIGURES 6 and 7. It will be recalled that the movement of collar 16, and resulting transverse motion of receiving surface 10^a, occur only when no workpiece is approaching the receiver, whereas the longitudinal motion indicated by the double-headed arrows takes place only when a workpiece is approaching the receiver. The result of this combination of movements is the workpieces are laid out flat on receiving surface 10^a in the form of two parallel stacks, one alongside the other.

Another embodiment of the invention, shown in FIGURES 8 and 9, is adapted to achieve the same result as that shown in FIGURES 6 and 7, but uses as the receptacle for block 81 of the crank assembly, a collar (not shown) having an appropriate recess for the reception of block 81, and driven to rotate 180° on each cycle. Such rotation can be achieved very simply by mounting the collar (similar to collar 16) directly over and connected to switch disc 34 (FIG. 2) which rotates 180° on each cycle, as previously described. Receiving surface 10^b is similar to receiving surface 10^a of FIGURES 6 and 7, but lacks channel-forming flanges 90 and is provided instead with a link 92 pivotally connected to the underside of receiving surface 10^b as at 94 and adapted to be pivotally connected to boss 86 as at 96.

As the crank assembly rotates, indicated by the curved

arrows, receiving surface 10^b is drawn by link 92 from the position shown in FIGURE 8, where it extends beyond one side of the supporting surface, to that shown in FIGURE 9, where it lies substantially directly over supporting surface 18, and back again, again resulting in the formation of a pair of parallel stacks of workpieces.

The operation of the reciprocating carriage having been fully described in any aforesaid Patent No. 3,113,771, it is not described at length herein. It may be noted, however, that as set forth therein, the sensing means, such as light source 98 and photocell 100 (FIG. 3) may be wired in parallel, or may be duplicated, using two photocells in tandem, so as to provide both (a) the means for enabling the reciprocating drive of the carriage when a workpiece is approaching and disabling it when a workpiece is not approaching (as more fully set forth in said patent), and (b) the means for enabling the position-changing means when a workpiece is not approaching and disabling it when a workpiece is approaching, as described above herein.

While this invention has been described with reference to certain preferred embodiments and illustrated by way of certain drawings, these are illustrative only, as many alternatives and equivalents will readily occur to those skilled in the art, without departing from the spirit or proper scope of the invention. The invention is therefore not to be construed as limited, except as set forth in the appended claims.

I claim:

1. Apparatus for receiving and stacking a succession of workpieces, said apparatus comprising in combination a generally horizontal, horizontally-reciprocating receiving surface, and means for periodically altering the position of said horizontally-reciprocating receiving surface with respect to workpieces delivered thereto and thereby altering the position on said receiving surface in which said workpieces are delivered.

2. An apparatus according to claim 1, further comprising means for disabling said means for altering the position of said receiving surface when a workpiece is in the process of being deposited on said surface.

3. Apparatus according to claim 2, wherein said disabling means comprises photosensitive means for detecting the presence of a workpiece approaching said surface.

4. Apparatus according to claim 1, further comprising drive means for imparting to said receiving surface a generally horizontal translational motion approximating the direction and velocity of an approaching workpiece.

5. Apparatus according to claim 1, wherein said means for periodically altering the position of said receiving surface comprises means for horizontally rotating said receiving surface through a portion of a circle.

6. Apparatus according to claim 1, wherein said means for periodically altering the position of said receiving surface comprises means for imparting a transverse horizontal translational motion to said receiving surface.

7. Apparatus according to claim 5, further comprising counter means for disabling said means for rotating said receiving surface, after each operation thereof, until a predetermined number of workpieces has been deposited on said receiving surface.

8. Apparatus according to claim 5, wherein said means for rotating said receiving surface is effective to alternate said receiving surface between two predetermined angular positions.

9. Apparatus according to claim 5, wherein said means for rotating said receiving surface is effective to advance said receiving surface sequentially in increments of substantially 90° through a series of complete rotations in a horizontal plane.

10. Apparatus according to claim 6, wherein said means for imparting translational motion to said receiving surface is effective to move said receiving surface alternately between two parallel positions spaced trans-

versely of the direction of delivery of workpieces to said receiving surface.

11. Apparatus for receiving and stacking a succession of workpieces comprising in combination a generally horizontal receiving surface, means for imparting to said receiving surface a first motion, said first motion being a horizontal translational motion approximating the velocity and direction of workpieces delivered to said receiving surface, means for imparting to said receiving surface a second motion effective to alter the position on said receiving surface to which said workpieces are delivered, means for enabling said means for imparting said first motion and disabling said means for imparting said second motion at times when a workpiece is being delivered to said receiving surface, and means for enabling said

5

10

15

means for imparting said second motion and disabling said means for imparting said first motion at times when a workpiece is not being delivered to said receiving surface.
